GASTON A. BRUNELLE, OF SAN FRANCISCO, CALIFORNIA

AUXILIARY AIR SUPPLY AND MIXING DEVICE FOR INTERNAL-COMBUSTION ENGINES

Application filed July 14, 1926. Serial No. 122,411.

My invention relates to auxiliary devices adapted to be interposed between a carburetor and the intake manifold of an internal-combustion engine for supplying air to the explosive charge issuing from the carburetor and for incorporating it therewith so as to cause a properly diluted and vaporized mixture to be delivered to the manifold.

The principal object of my invention is to produce a device of this character which thoroughly incorporates the air with the explosive charge from the carburetor and causes the mixture to be automatically delivered in correct combustible quality to the manifold at all speeds of the engine.

Another object of the invention is to provide a device adapted to minimize the liability to carbon deposits and to cause a smooth and virtually noiseless running of the engine.

Further objects of the invention are to produce a device, which is simple in construction and cheap to manufacture, and a device, which can be easily attached, easily assembled or disassembled, and has no parts liable to get out of order.

A preferred embodiment of the invention is described in detail hereinafter and is illustrated in the accompanying drawings, in which:

Figure 1 is a side elevation of a device constructed according to the principle of my invention and interposed between a carburetor and the intake manifold of an internal-combustion engine;

Figure 2 is a mid-sectional elevation of the device shown in Figure 1;

Figure 3 is an end elevation of the flange element of the device, the view being taken along the line 3—3 in Figure 1;

Figure 4 is a bottom plan of the outer valve;

Figure 5 is a bottom plan of the seat member for the outer valve; and

Figure 6 is a horizontal section of the flange element, the view being taken along the line 6—6 in Figure 3.

My device as a whole is indicated in the drawings by the numeral 1 and consists of a flange element 2, which has bolt holes 3 therein, so that the element is adapted to be interposed between the flanged outlet of a car-

buretor 4 and the flanged intake manifold 5 of an internal-combustion engine and firmly bolted thereto by usual securing means 6. The intake manifold 5 is provided with the usual throttle valve (not shown in the drawing). It is thus evident that the throttle valve is disposed between the element 2 and the engine proper. This element has therethrough an opening 7 and is preferably formed with a downward, internally threaded extension 8 and provided with a passageway 9 which leads from the interior of the extension and communicates with the opening 7, within which a baffle plate 10 of arcuate form, as is most clearly shown in Figure 6, is secured to the flange element between the passageway 9 and the intake manifold, and the element is formed with a wall 11 sloping from the passageway toward the carburetor.

A cylindrical valve housing 12 having an upward, internally threaded extension 13 is secured to and below the flange element by means of a nipple 14, screwed into the extension 8 and the extension 13, which has therein an aperture 15, so that thus the interior of the housing communicates with the opening 7 through the aperture, the nipple and the passageway 9. The valve housing is internally threaded and is adapted to have screwed therein a member 16 provided with a valve seat 17 and an interior wall 18, which extends from the valve seat and forms through the member a passage 19 communicating with the atmosphere, and in its outer or under side the member has radial slots 20 communicating with the passage.

A valve 21, also provided with a valve seat 22, is normally adapted to be seated on the seat 17 by gravity and has a stem 23 extending through the member 16 in a spaced relation to the wall 18. The valve 21 is further provided with an interior wall 24, which extends from the seat 22 and forms through the valve and the stem another passage 25 communicating with the atmosphere. Upon the stem 23 and near the end thereof is secured a flange 26, and the end of the stem has therein radial slots 27 communicating with the passage 25.

A second valve 28, normally adapted to be

seated on the seat 22 by gravity, and provided with a stem 29, which extends through the valve 21 and is in a spaced relation to the wall 24, may have the end of the stem threaded for securing thereon a nut 30, which is adapted to abut the end of the stem 23 for limiting the movement of the valve 28 relative to the valve 21.

In operation, when the engine is running at a slow or a normal, predetermined speed, the valve 21 is lifted by the suction of the engine sufficiently to allow a current of air to pass through the passage 19 into the interior of the housing 12 and thence to the opening 7 and against the baffle plate 10, where it will be thoroughly incorporated with the mixture of air and hydro-carbon vapors from the carburetor and whence it will be drawn therewith into the intake manifold. At this slow or normal speed of the engine the suction is sufficient to lift the valve 21 only so far that the flange 26 abuts the underside of the member 16 and allows air to pass through the slots 20 without lifting the valve 28 from its seat 22. As soon as this normal speed is exceeded, the increased engine suction causes the valve 21 to be lifted so that the flange 26 abuts the underside of the member 16 and also so that the valve 28 is lifted from its seat 22 at the same time. If the suction is sufficiently increased, the valve 28 will thus be lifted until the nut 30 abuts the valve stem 23. In this manner an additional air supply is caused to be drawn through the slots 27 and the valve passage 25 to the opening 7 and to be commingled with the combustible mixture from the carburetor, so that the mixture is thus thoroughly diluted and vaporized when it passes from the intake manifold to the engine.

It should be observed that, while the nut 30 limits the upward movement of the valve 28, the flange 26 limits the upward movement of the valve 21, and that the valves are returned to their respective seats by gravity so that my device is thus entirely automatic in its operation. In Figure 1 the flange element 2 is shown as secured between the flange at the side of the carburetor 4 and a corresponding side flange at the intake manifold 5, but it is understood that the flange element may be secured in other positions, if so required, for connecting a carburetor with an intake manifold, and the device may otherwise be so modified in its construction as to adapt it for use in connection with various makes of carburetors and intake manifolds for various makes of internal-combustion engines without departing from the spirit of my invention and without going beyond the scope of the appended claim.

I claim as my invention:

An auxiliary air-supply and mixing device comprising an element provided with an opening therethrough and adapted to be in-

terposed between the outlet of a carburetor and the intake manifold of an internal-combustion engine; a valve housing connected with the element and having its interior in communication with said opening; a member provided with a valve seat and secured in the housing, said member having an interior wall, which extends from the valve seat and forms through the member a passage communicating with the atmosphere, and the outer side of the member having slots therein communicating with said passage; a gravity actuated valve provided with a valve seat therein and normally adapted to be seated on the seat in said member, said valve having a stem extending through the member in a spaced relation to said wall and being provided with a flange secured to the stem near the end thereof, and the valve also having an interior wall, which extends from the seat in the valve and forms through the valve and the stem another passage communicating with the atmosphere, the end of the stem having slots therein communicating with the passage through the valve; a second gravity actuated valve normally adapted to be seated on the seat in the first mentioned valve and provided with a stem, which extends through the first mentioned valve and is in a spaced relation to the interior wall thereof; and means secured to the stem of the second valve and adapted to abut the stem of the first mentioned valve for limiting the movement of said second valve relative to the first mentioned valve.
